(57) **CLAIM**

We claim the ornamental design for a display screen or portion thereof with a graphical user interface, as shown and described.

DESCRIPTION

The patent file contains at least one drawing executed in color. Copies of this patent with color drawings will be provided by the Office upon request and payment of the necessary fee.

The single FIGURE is a front view of the display screen or portion thereof with a graphical user interface showing the claimed design.

The outermost broken lines in FIGURE shows a display screen or portion thereof, and form no part of the claimed design. The broken line showing of text forms no part of the claimed design.

The grayscale shows a contrasting appearance.
